UNITED STATES PATENT OFFICE

RUSSELL E. JONES, OF LEBANON, PENNSYLVANIA

STEAM BOILER

Application filed June 4, 1928. Serial No. 282,613.

The present invention relates to steam or hot water boilers, and while it is essential in the type of boiler hereinafter set forth and claimed, to provide inclined water tubes in both directions, either from the front to the rear, or from side to side of the fire box, it is the main purpose to provide improved means, in a boiler of this kind, to provide for mechanical separation between the upper and lower parts of the water space formed between the walls of the fire box and the shell walls of the boiler, and thereby providing for greater and more efficient circulation of water, which is particularly essential in boilers of this character.

Another purpose, in a boiler of this kind, is to provide the fire box end plates and the shell walls adjacent the ends of the water tubes with corresponding bulged portions, or to provide the fire box end plates with bulges or the said end plates inclined at right angles to the axis of the tubes with the outer shell walls adjacent the ends of the tubes straight, thereby providing for a mechanical separation between the upper and lower parts of the water space.

The purpose of this latter construction, over the corresponding bulged parts of the fire box end plates and the adjacent shell walls, is to provide for greater and more efficient circulation of the water.

Another purpose is to provide, in a boiler of this kind, baffles to be located at suitable positions between certain of the water tubes, preferably at the lower ends of such tubes, and above the tubes at the center thereby providing for defusing the heat over the entire heating surface.

This construction may be used in all constructions of boilers, either for the super-power boilers, or in boilers used in houses or dwellings, for heating purposes, and in such instances the outlet for the products of combustion may be taken from either side horizontally or taken through the top of the fire box crown sheet disclosed in the drawings.

A further purpose is to provide cover plates for the ends of the tubes, either individually for each tube, or for a group of tubes. In some instances the boiler walls

may have caps for each tube adjacent where the ends of the water tubes are located.

A still further purpose is to provide access doors in the outer shell of the boiler and in the opposed walls, thereby permitting access to the water tubes when cleaning, repairing or replacing the water tubes.

Furthermore it is the aim to provide stay bolts or braces for use throughout the boiler for connecting the outer shell wall and the fire box wall, said stay bolts or braces being located and pitched suitable to the pressure and conditions.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:—

Figure 1 is a view in side elevation of the improved boiler constructed in accordance of the invention and showing one of the side walls broken away to illustrate the internal construction as well as the construction of the walls of the boiler.

Figure 2 is a front end view of the boiler.

Figure 3 is a view similar to Figure 2, but showing a modified form of a smaller boiler for use in dwellings such as small homes and the like, and wherein the water tubes are from side to side, with the mechanical separation between upper and lower parts of the water space.

Figure 4 is a side view of Figure 3, showing parts of the shell wall broken away.

Figure 5 is a side view similar to Figure 1 with the side wall broken away, and illustrating the fire box end plates and the shell walls opposite the ends of the water tube both bulged.

Figure 6 is a detailed view showing the end plates of the outer shell 12 provided with caps axially aligned with the water tubes in order to permit the tubes to be cleaned, replaced or repaired.

Referring to the drawings, 1 identifies the foundation of the boiler, which may be constructed of any suitable material preferably concrete or brick, and on which the base 2 of the boiler is supported. This base may be of steel or brick.

The boiler includes a fire box 3 and an ash pit 4, which has a front plate 5 provided with the usual ash pit doors 6.

10 The usual grate bars 7 are supported on the grate bearer bars 8. The grate bars divide the fire box from the ash pit, the latter being counter-sunk to provide for increased space for the ashes and to facilitate the removal thereof.

15 The fire box 3 has the usual fire box doors 9 having preferably circular dampers 10.

20 The body of the boiler comprises the inner fire box shell 11 and the outer boiler shell 12. The former is constructed preferably of steel plate material, and the fire box end plates 13 of the shell 11 are bulged or inclined opposingly and at right angles to the axis of the water tubes 14, and 15, which are 25 inclined in both directions, intersecting approximately at the vertical center of the boiler, that is the center between the front and rear of the boiler. The water tubes are mounted in the fire box plates in the usual manner with their ends preferably flared in 30 position as at 16.

35 In Figures 1 and 2 there are cover plates 17 at the ends of the outer shell 12 which are vertical, and are bolted in position, and where they engage with the shell 12 gaskets 18 of suitable material are interposed between the plates and the shell 12, to insure 40 secure joints. These cover plates 17 are disposed relatively close to the apexes of the inclined fire box end plates 13, but not close enough to entirely shut off communication between the upper and lower parts 19 and 20 of the water space 21, but sufficiently close as to provide for a mechanical separation 45 between the upper and lower parts 19 and 20 of said water space in order to provide for greater and more efficient circulation of the water.

50 In Figures 3 and 4 the water tubes are inclined in both directions from side to side of the boiler, otherwise the construction in Figures 3 and 4 is practically identical with that in Figures 1 and 2, however, with the exception that the boiler disclosed in Figures 55 3 and 4 is particularly adapted for dwellings such as small homes and the like.

50 Suitable baffles 22 are arranged between certain of the tubes 14 and 15 at their lower ends, which forces direction and concentrates 60 the heat on the center of the water tubes, there being a V-shaped baffle 23 located at the center of the upper water tubes, and which latter baffle diverges the heat in directions toward the opposite upper ends of 65 the water tubes. In this manner the fire box

is provided with circuitous courses which causes the heat to be defused over the entire heating surface. As shown in Figure 2, while the heat travels in undulated courses as indicated by arrows in Figure 1, the heat also ascends in undulated courses vertically between the tubes, that is in Figure 2, said undulated courses in this instance being caused due to the positioning of the water tubes relatively close side by side.

75 The upper part of the boiler has a steam chamber 24, and leading from the upper part of the fire box at one side of the boiler is an outlet 25 for the smoke or products of combustion, there being a suitable damper 26 of conventional type for controlling the discharge of the products.

80 Suitable access doors 27 are located on the sides of the boiler, while in Figures 3 and 4 the access doors are on the front and rear end plates of the boiler, allowing access to the water tubes, for the purpose of removing the soot from between the tubes and to facilitate inspection.

85 Suitable hand holes 28 are provided in the outer shell of the boiler, while 29 identifies return and blow-off pipe connections on both sides of the boiler, whereby inlet and outlet pipe connections not shown may be made, for conducting the water to the water space and for removing it.

90 The cover plates 17 of the outer shell 12 of the boiler are fastened in position by stud bolts and nuts 30.

95 The top wall of the outer shell has a flanged opening 31, whereby a safety valve or water relief valve connection not shown may be provided, for permitting escape of excess pressure in the boiler. The top wall of the outer shell 12 of the boiler is also provided with a flanged opening 32 to provide for steam or hot water take-off connections not shown, whereby the steam or hot water may be conducted to various points of consumption.

100 Suitable stay bolts and braces 33 are provided and are adapted for use throughout the wall of the boiler connecting the outer shell and the fire box, and are located and pitched to suitable pressure and conditions, while suitable anchor bolts 34 are provided for the purpose of anchoring the ash pit front to the base 2.

105 Referring to Figures 3 and 4, the construction of boiler is substantially the same as that in Figures 1 and 2 with the exception that the water tubes are inclined from side to side, and in this instance the outlet 25a, that is for the products of combustion leaves the boiler from the crown sheet 35 to the rear, adapting this boiler particularly for use in small dwellings.

110 Referring to Figure 5 the construction of boiler is the same as in Figure 1, with the exception that the cover plates 17a and parts 115

of the shell 12 are inclined correspondingly to the inclination of the fire box and plates 13, thereby making a uniform water space 19.

Referring to Figure 6 the end plates 12b are provided with suitable caps 36 axially aligned with the ends of the water tubes so as to permit scaling, repairing or replacement of the tubes.

Should it be found desirable to install 10 boilers of this character where it is the aim to burn oil, the grate bars 7 may be omitted, and a conventional type of oil burner, not shown, may be installed in the usual manner.

Referring to Figures 2 and 4 it will be 15 noted that the outlets 26 and 25a may have a back door as identified at 26a, which may be counter-balanced in any well known manner not shown with the damper 26b more clearly shown in Figure 4 at the rear lower 20 portion of the boiler adjacent the ash pit. Obviously this boiler may be used as hot water boiler instead of a steam boiler, in which case as in Figure 4 the entire water space 21 may receive water.

23 The invention having been set forth, what is claimed is:

1. A boiler including a fire box inner shell and an outer boiler shell provided with a steam chamber above the top wall of the 30 fire box, two groups of water tubes each comprising a plurality of series of water tubes inclined upwardly in both directions from opposite walls of the fire box, the series of one group alternating with the series of the other group, baffles arranged between the lower ends of said lower water tubes and said fire box walls and a V-shaped baffle disposed upon the upper water tubes and corresponding to the central formation of the arrangement of said tubes, said both sets of baffles providing circuitous courses for undulated passage of the heat, and means located centrally between the groups of tubes where they connect with the fire box end plates for mechanically separating a water space between 45 the fire box shell and the outer boiler shell, providing for greater and more efficient circulation.

2. A boiler including a fire box inner shell and an outer boiler shell and having a water space between the two shells, a steam chamber above the crown sheet of the fire box shell communicating with said water space, two groups of water tubes each comprising a plurality of series of water tubes communicating with the water space and being inclined upwardly in both directions from the opposite walls of the fire box, the series of one group alternating with the series of the other group, a V-shaped baffle being centrally arranged and disposed between the top of the water tubes and said fire box walls, said baffle being substantially shorter than the tubes, and baffles arranged between and at the ends of certain lower water tubes and

said fire box shell thereby causing undulated courses for the heat, and means located centrally between the groups of tubes where they connect with the fire box end plates for mechanically separating a water space between the fire box shell and the outer boiler shell, providing for greater and more efficient circulation.

In testimony whereof he affixes his signature.

RUSSELL E. JONES
